UNITED STATES PATENT OFFICE.

KARL C. RANDALL, OF EDGEWOOD PARK, PENNSYLVANIA, ASSIGNEE TO WESTINGHOUSE ELECTRIC AND MANUFACTURING COMPANY, A CORPORATION OF PENNSYLVANIA.

CIRCUIT-INTERRUPTER.

1,264,333.

Specification of Letters Patent. Patented Apr. 30, 1918.

Application filed August 2, 1913. Serial No. 782,548.

To all whom it may concern:

Be it known that I, KARL C. RANDALL, a citizen of the United States, and a resident of Edgewood Park, in the county of Allegheny and State of Pennsylvania, have invented a new and useful Improvement in Circuit-Interrupters, of which the following is a specification.

My invention relates to circuit interrupters and particularly to knife-blade switches of the quick-break type.

The object of my invention is to provide a knife-blade switch of the quick-break type, the quick-break attachment of which shall be of such construction and have such co-operative relation with the other parts of the switch that injury to the co-operating contact portions by arcing and pitting shall be prevented.

20 A further object of my invention is to provide a knife-blade switch, the jaw contact members of which are so formed as to insure prompt rupture of such arcs as may be produced when the switch is opened.

25 Knife blade switches which have heretofore been provided with quick-break attachments, have been reasonably effective within certain limits, as regards the amount and character of the energy interrupted, but, beyond certain well defined limits, the arcs produced at the instant of separation between the quick-break attachment and the contact jaws have injuriously pitted or burned the contact surfaces to such an extent as to materially impair the usefulness of the switches.

30 My present invention is intended to provide a means for use in connection with circuits carrying relatively large amounts of energy and to provide for the final interruption of the circuit between portions of the contact members of the switch which are not in engagement under any condition.

35 In the accompanying drawing, Figure 1 is a view, mainly in side elevation, but partially in section, of a switch embodying my invention, and Fig. 2 is a detail view of parts of the contact members shown in Fig. 1.

40 The main contact blade 1 of the switch shown in the drawing is pivotally supported by one of the terminals 2 and is movable on such pivotal support into and out of en-

gagement with the jaws 3 of the other switch terminal. The members 2 and 3 are mounted upon an insulating base or panel 4 and have cylindrical screw-threaded projections which extend through holes in the part 4 and are provided with terminal connecting devices 5 at the rear of the panel, in accordance with the usual practice. The switch blade 1 is provided with an operating handle 6 and with a quick break attachment device 7, the ends 8 and 9 of which are bent laterally in opposite directions but in the same plane. The laterally bent end 9 of the attachment device 7 is pivotally attached to the blade member 1 at 10, and the outer edge of its body portion is normally held in engagement with the inner edge of the blade 1 by means of a spring 11. The laterally bent free end 8 of the member 7 is rounded to serve as the terminal at which the final rupture of any arc which may be formed by opening the switch occurs.

45 The main body portions of the jaw terminal 3 are substantially parallel to make effective contact with the sides of the blade 1, but the outer ends 12 of such jaw members diverge from each other to form a space 13 of substantially V-shape. The portion 8 of the member 7 is adapted to remain out of engagement with the outer ends 12 of the jaw members under all conditions.

50 Assuming that the switch is closed and the circuit in which it is connected is carrying current, the switch blade 1 will be moved outwardly by means of the handle 6 and, on account of the friction between the member 7 and the jaw surfaces, the spring 55 11 will yield sufficiently to permit the blade 1 to become separated from the jaws before the member 7 is unseated. When the tension upon the spring 11 becomes sufficient to effect withdrawal of the member 7, 60 the latter will spring from its seat in the jaws with a quick snap action, and the final rupture of such arc as may be formed will be at a point on the portion 8 of the member 7 that is not in contact engagement 65 with the jaws under any condition. Furthermore, the divergence of the ends of the jaw members tends to spread such arcs as may be formed and interrupt the same more quickly than would otherwise be the case.

70 100 105 Minor variations as to the size, shape and

relative arrangement of parts may be made within the scope of the appended claims without departing from my invention.

I claim as my invention:

5. 1. In a circuit-interrupting device, the combination with a knife-blade member and contact jaws having non-engaging portions, of a quick-break attachment having a portion thereof that never engages the contact jaws but is adapted to coöperate with the non-engaging portions of the contact jaws to receive the arc that is drawn when the device is opened.
10. 2. A knife-blade switch comprising a main knife-blade member, contact jaws having non-engaging portions, and an auxiliary quick-break knife-blade member having a portion that is adapted to remain out of engagement with the contact jaws under all conditions and to receive the arc from the non-engaging portions of the contact jaws when the switch is opened.
15. 3. A switch comprising a stationary contact member having a non-engaging arcing portion and a movable contact member having a non-engaging portion adapted to coöperate with the non-engaging portion of the stationary contact member to receive the final break of the arc that is drawn when the switch is opened.
20. 4. A switch comprising a knife-blade member having a non-engaging portion and contact jaws therefor having non-engaging portions that coöperate with the non-engaging portion of the knife-blade member to receive the arc that is drawn when the switch is opened.

5. A switch comprising a stationary contact member having a non-engaging arc-extinguishing portion and a movable contact member having a portion for coöperating only with the non-engaging arc-extinguishing portion to receive the arc that is drawn when the switch is opened. 40

6. A switch comprising contact jaws having non-engaging diverging outer ends and a knife-blade member having a lateral projection at its outer end that is adapted to remain out of engagement with the contact jaws and to coöperate with the diverging outer ends thereof to receive the arc that is drawn when the switch is opened. 45

7. A switch comprising contact jaws having non-engaging diverging outer ends and a knife-blade member therefor having a laterally extending outer end that is adapted to pass between, but out of engagement with, the diverging outer ends of the jaws to receive the arc that is drawn when the switch is opened. 50

8. A switch comprising a stationary contact member having a non-engaging portion and a movable contact member having a non-engaging portion to coöperate with the non-engaging portion of the stationary contact member to receive the arc that is drawn when the switch is opened. 60

In testimony whereof I have hereunto subscribed my name this 26th day of July, 1913.

KARL C. RANDALL.
